F. TOBIAS.
NECKTIE STRETCHER.
APPLICATION FILED APR. 16, 1918.

1,277,667.

Patented Sept. 3, 1918.

UNITED STATES PATENT OFFICE.

FRANK TOBIAS, OF TIFTON, GEORGIA.

NECKTIE-STRETCHER.

1,277,667.

Specification of Letters Patent. Patented Sept. 3, 1918.

Application filed April 16, 1918. Serial No. 228,916.

To all whom it may concern:

Be it known that I, FRANK TOBIAS, a citizen of the United States, residing at Tifton, in the county of Tift and State of Georgia, 5 have invented certain new and useful Improvements in Necktie-Stretchers, of which the following is a specification.

This invention relates to apparel apparatus, and more especially to garment stretchers; and the object of the same is to produce 10 a simple instrument by means of which the ordinary four-in-hand tie may be placed under tension and left there over night so that in the morning it may not be wrinkled when

15 the wearer comes to put it on.

Another object is to produce a simple and economical apparatus of this kind which is an ornament to the dresser and a useful piece of bedroom furniture.

20 Other objects will appear in the following specification and claims, and attention is invited to the accompanying drawings, in which:—

Figure 1 is a side elevation of this kind 25 with the side door open,

Fig. 2 is a horizontal section on the line 2—2 of Fig. 1 with the side door closed,

Fig. 3 is an end elevation with both doors open,

30 Fig. 4 is a sectional detail illustrating the cross rod.

Mounted on legs 1 if desired, is a box-like body 2 having a roller 3 whose trunnions 4 are rotatably mounted in the side walls at 35 one end of the body. One of said walls is cut away to produce a long opening 5 adapted to be closed by a side door 6 which is hinged at 7 as shown, but the end portion and the top portion of this side wall remain 40 to provide means for supporting the roller already mentioned and the upper clip yet to be described. One end of the device may also be left open, to be closed by a hinged door 8, and it is quite possible that the top of 45 this device may have a door whose handle or knob only is indicated at 9 in Fig. 1.

Within the body toward what might be called the front end thereof is secured on the bottom a lower clip broadly indicated 50 by the numeral 10. The structure of this clip is not important, except that it should have spring-closed jaws and a thumb piece which may be pressed upon to open the jaws and thereby release the tie, the latter being 55 indicated by the letter T. An upper clip is also provided, preferably disposed above the

lower clip mentioned and of appropriate formation. I prefer that it also shall have jaws and thumb pieces as shown, and its two members indicated by the numerals 11 and 12 are pivotally mounted on a rod 13 and actuated by springs 14 as usual. Between these springs is a block from which a spring 16 leads forward between the thumb pieces and is attached to a cross rod within the front end of the casing or body 1. This spring is shown in Fig. 1 as being helical, but it is quite possible to use a stout rubber, and its sole purpose is to draw the upper clip forward.

The rod 17 best shown in Fig. 4 has a block 18 at its center to which the spring is attached. At opposite ends of the block are pins 19, and, beyond the latter springs 20 are coiled on the rod and bear at their outer ends against thumb pieces 21 carried by collars 22, the latter being slidably mounted on the rod and pressed normally outward so that their extremities may project into holes 23 disposed in pairs in the sides of the body 2 as shown. Thus the position of the rod 70 may be adjusted to permit the device to work on ties which are somewhat shorter than herein shown.

In the use of this device the tie T is fastened at one end in the lower clip as shown in Fig. 1, led thence around the roller 3 and fastened at its other end within the upper clip, the latter being moved or pressed rearward to put the spring under tension 80 before engaging its jaws with the tie. The result is that, when this clip is released, the tension of the spring 16 is exerted to draw on the tie and stretch the latter, or at least hold it taut, and yet the entire device is 85 only half the length of an ordinary four-in-hand necktie and is not a cumbersome addition to the bureau or dresser. I have shown doors in the top, side, and front end but would not be limited in this particular, and 90 in fact the entire body might be an open-work structure so long as there was sufficient material to afford journals for the trunnions 4 of the roller and means for mounting the lower clip and the cross rod 95 somewhere within the body.

The foregoing description and the drawings have reference to what may be considered the preferred or approved form of my invention. It is to be understood that 100 I make such changes in construction and arrangement and combination of parts, ma-

terials, dimensions, et cetera, as may prove expedient and fall within the scope of the appended claims.

Having thus fully described my invention, what I claim as new and desire to secure by Letters Patent, is:—

1. In a garment stretcher, the combination with a body, a roller journaled in one end thereof, and means at the other end for attaching one end of said garment; of means at the last-named end adapted for attachment to the other end of the garment, and a tension device impelling said last-named means away from the roller.
2. In a garment stretcher, the combination with a body, and a transverse roller journaled in one end thereof; of a clip fixed in the other end of the body, a movable clip in this end of said body, and a spring drawing it normally away from said roller.
3. In a garment stretcher, the combination with a box-like body provided with doors, and a roller having trunnions journaled in the sides of said body at one end thereof; of a clip fixed on the bottom of the body at the other end thereof, a movable clip above that named, and yielding means drawing it away from said roller.
4. In a garment stretcher, the combination with a box-like body provided with doors, and a roller having trunnions journaled in the sides of said body at one end thereof; of a clip fixed on the bottom of the body at the other end thereof, a movable clip disposed above that named, a cross rod within this end of the body, and a contractile spring connecting this rod with the last-named clip, for the purpose set forth.
5. In a garment stretcher, the combina-

tion with a box-like body having part of one side open, a door for closing this side, and a roller having trunnions journaled in the fixed portion of this side and in the other side; of a spring clip fastened to the bottom of the body, a second spring clip, a cross rod whose extremities are connected with the sides of the body near that end opposite the roller, and a contractile spring connecting this rod with said last-named clip and drawing it normally away from the roller, for the purpose set forth.

6. In a garment stretcher, the combination with a box-like body having openings disposed in pairs in its sides near one end, a clip beneath said openings, and a roller at the other end; of a longitudinally extensible rod selectively engaged with the openings of said pairs, and a second clip carried by said rod above the first clip.

7. In a garment stretcher, the combination with a box-like body having openings disposed in pairs in its sides near one end, a clip beneath said openings, and a roller at the other end; of a cross rod above the clip, pins through its body, expansion springs outside said pins, and collars slidably mounted on the ends of the rod and having thumb-pieces against the outer extremities of said springs, the outer ends of the collars adapted for selective engagement with a pair of said openings, and a second clip connected with the center of this rod.

In testimony whereof I affix my signature in presence of two witnesses.

FRANK TOBIAS.
